UNITED STATES PATENT OFFICE.

LEO J. GRUBMAN, OF NEW YORK, N. Y., ASSIGNOR TO VOICES, INCORPORATED, OF NEWARK, NEW JERSEY, A CORPORATION OF DELAWARE.

SOUND-PRODUCING DEVICE.

Application filed January 11, 1924. Serial No. 685,500.

This invention relates to sound producing devices of the character commonly incorporated in the body of a doll or other toy for producing a characteristic cry upon the proper manipulation of the toy and more particularly to that type of such devices wherein a bellows is employed having a movable head and enclosed within a suitable casing. The subject matter of the present application is disclosed in a general way in my Patent No. 1,507,826, Sept. 9, 1924, and is principally concerned with an improved means for easily, quickly and securely attaching one end of the tubular flexible bellows wall to the movable bellows head.

It is a more particular object of my present disclosure to provide means for exerting a uniform frictional clamping action upon the end edge of the flexible bellows wall to tightly hold or secure the same at all points to the marginal portion of the bellows head, thereby dispensing with the use of adhesives, tacks or other similar fastening means for this purpose.

In one embodiment of my present invention, I provide means whereby the frictional clamping element for the flexible bellows wall is tightly secured in connection with the bellows head by a frictional clamping ring so that any possibility of accidental separation of the parts will be effectively obviated.

With the above and other objects in view, the invention consists in the improved sound producing device and in the form, construction and relative arrangement of the several parts to be hereinafter more fully described, illustrated in the accompanying drawing, and subsequently incorporated in the subsequently joined claims.

In the drawing wherein I have disclosed several simple and practical embodiments of my present improvements and in which similar reference characters designate corresponding parts throughout the several views:

Figure 1 is a sectional view through a sound reproducing device showing one embodiment of my invention;

Figure 2 is a plan view of the end closure of the housing or casing removed; and,

Figure 3 is a vertical section through another form of bellows head showing an alternative means for connecting the flexible wall thereto.

The particular features of construction constituting the subject matter of my present application are herein illustrated as embodied in a sound producing device of that type wherein the several operating parts are enclosed within a shell or casing 5 having metal caps or closure plates 6 and 7 respectively, applied to the opposite ends thereof. Between these casing ends the axially positioned guide member 8 is arranged.

A bellows is also enclosed within the shell or casing 5, said bellows including a flexible tubular body wall 9 having one of its end edges frictionally clamped and secured over one end edge of the casing wall by the closure plate 7, while the other end edge of said flexible bellows wall is connected to the gravity movable head 10 which is supported and guided in its movement by the member 8. As herein shown this member is of tubular form and within the same a suitable sound producing reed indicated at 11, is mounted, said reed being located adjacent to an opening in the wall of said member affording communication between the interior thereof and the bellows chamber. The movable bellows head 10 and the member 8 are also provided with coacting means whereby the emission of sound produced by the expulsion of air through the reed 11 is automatically controlled in the gravity movement of the bellows head 10 in one direction. No claim is herein made to this mounting and arrangement of the bellows head or the automatic sound emission control means, since such subject matter is fully described and claimed in an application for patent filed by me on March 11, 1922, Ser. No. 542,884. The novel feature of the present disclosure is confined to

the means employed for connecting the flexible tubular wall 9 of the bellows to the head 10, which I have herein illustrated in several alternative forms. Also, no claim is made in this application to the means for attaching the other end edge of the flexible bellows wall to the end of the wall of the casing 5, as this subject matter is particularly described and claimed in my prior pending application first above referred to.

In the construction illustrated in Figures 1 and 2 of the drawings the head 10 is in the form of a plain disc and the end edge of the flexible bellows wall 9 is turned inwardly over the edge of this disc. In this embodiment

ment of the invention I provide a cup-shaped member 16 having a marginal flange 17 of angular cross-sectional form to engage upon the inwardly turned end edge of the flexible bellows wall and clampingly secure the same tightly upon the peripheral surface of said bellows head and upon the upper surface of said head at its marginal edge. The body portion of the member 16 is disposed in spaced parallel relation to the head 10, thus forming between said member and the head a sound receiving chamber 18, the member 16 being provided with a plurality of openings 19 for the emission of sound from said chamber during the gravity movement of the bellows head. It will be understood that in this construction both the head disc 10 and the wall 16 have parts slidingly engaged upon the member 8 which operate to interrupt the emission of sound from said tubular member into the chamber 18.

In Figure 3 of the drawings, the movable bellows head 10 is provided upon its outer side and in spaced relation to its periphery with the annular flange 20. The flexible bellows wall is turned over the outer edge of the head and against the flange 20 and frictionally clamped in place by means of a continuous clamping ring 21 of angular cross-sectional form.

It will be apparent that by providing the head with the annular flange 20 in this instance likewise, the ring 21 which is of angular cross-sectional form, frictionally clamps the end edge of the flexible bellows wall against two angularly related surfaces of the bellows head. Thus in both constructions herein described the means which I provide for connecting the end of the bellows wall to the movable head provides a relatively extensive area of frictional clamping contact between said flexible wall and the bellows head, thus insuring a positive and reliable connection of these parts without the use of adhesives, tacks or other similar fastening means whereby the possibility of their accidental separation is obviated.

From the foregoing description considered in connection with the accompanying drawing, the construction, manner of operation and several advantages of the illustrated embodiments of the device will be clearly understood. It will be seen that I have entirely dispensed with the use of adhesives and other means heretofore used in the art which have been found objectionable primarily for the reason that they prevent the rapid assemblage and connection of the parts and are also more or less unreliable in the functional operation of the device. My improved means for connecting the movable air expelling head to the flexible wall of the bellows as herein described, has been found entirely satisfactory in practical operation and affords a very simple and inexpensive

means which not only produces a secure and reliable connection but also enables the parts to be properly assembled with great rapidity.

In my present disclosure I have illustrated several practical examples for accomplishing the desired purpose, but it is to be understood that they are merely suggestive and that the essential feature might also be exemplified in various other alternative constructions, and I accordingly reserve the privilege of resorting to all such legitimate changes in the form, proportion and relative arrangement of the several parts as may be fairly embodied within the spirit and scope of the invention as claimed.

I claim:—

1. A sound producing device of the character described comprising a bellows and a gravity actuated weight for collapsing and distending said bellows, a sounding device operated by the air expelled from said bellows, articulating means for articulating the sound produced by said sounding device, said articulating means comprising means for periodically interrupting the sound produced by said sounding device and an encircling clamping ring for connecting one end of said bellows with said weight, said ring having an inturned flange adapted to extend over part of said weight.

2. A sound producing device of the character described, comprising a bellows consisting of a flexible body wall and a gravity actuated weight for collapsing and distending said bellows, a sounding device operated by the air expelled from said bellows, articulating means for articulating the sound produced by said sounding device, said articulating means comprising means for periodically interrupting the sound produced by said sounding device, and an annular member of angular cross-sectional form adapted to be engaged over the end edge of the flexible bellows wall to frictionally clamp the same upon angularly extending surfaces of said gravity actuated weight.

3. A sound producing device of the character described, comprising a bellows consisting of a flexible body wall and a gravity actuated weight for collapsing and distending said bellows, a sounding device operated by the air expelled from said bellows, articulating means for articulating the sound produced by said sounding device, said articulating means comprising means for periodically interrupting the sound produced by said sounding device, and an annular part of angular cross-sectional form adapted to be engaged upon one end edge of the flexible bellows wall to frictionally clamp the same against the peripheral surface of said gravity actuated weight and against one side face thereof.

4. In a sound producing device, a bellows having a tubular flexible wall fixed at one

of its ends, a sounding reed, a movable head for the other end of the bellows to expel air therefrom through said reed, said head having adjacent angularly related surfaces, and a permanently annular, structurally continuous member having frictional clamping engagement upon the latter end edge of the flexible bellows wall to clamp the same against the circumferential angularly related surfaces of said head, said member adapted to be moved axially of the head upon the edge of the bellows wall in the assemblage of the parts, and one of said surfaces constituting a stop to limit such axial movement of said member to its clamping position.

5. A bellows for sound producing devices, having a tubular flexible wall, a head for one end of said bellows, an annular non-expansible clamping member, one end edge 20 of such flexible wall adapted to be interposed between said head and said clamping member, and said head and clamping member moved relatively to each other axially of the bellows head to clamp said end edge 25 of the flexible wall between said annular member and a part of said head, and said head and clamping member having opposed surfaces frictionally engaging opposite sides of said flexible wall and limiting such relative axial movement of the parts.

In testimony that I claim the foregoing as my invention, I have signed my name hereto.

LEO J. GRUBMAN.
